SPINDLE

Winslow S. Pierce, Jr., Dublin, N. H.

Application June 17, 1948, Serial No. 33,620

7 Claims. (Cl. 57—130)

1

This invention relates to spindles and more particularly to high-speed rotating spindle assemblies for use in driving bobbins or cop tubes on which textile strands are spun, twisted or wound.

Textile strands are spun on bobbins mounted on spindles. It is essential to the economical utilization of the spinning equipment that the spindles rotate at very high speeds. At desired operating speeds, various vibrations occur due primarily to irregularities in the winding of the yarn, thread or other textile strand onto or from the bobbin. Such vibrations cause excessive wear or breakage of the spindle bearings, or breakage of the bobbin or other equipment, and the rotative speeds that can be employed are practically limited by the magnitude or violence of these vibrations.

According to the present invention it is proposed to provide an improved spindle and bobbin carrying assembly which will eliminate or minimize vibrations due to changing eccentric disposition of the weight with respect to the axis of the spindle bearings such as results from irregular winding of a textile strand on a bobbin carried by the spindle. In general, this is accomplished in accordance with the invention by employing a relatively long flexible spindle blade carried at its lower end by a fixedly journaled rotative driving base and connected at its upper end to the upper end of a rigid bobbin carrying sleeve.

The lower end of the bobbin sleeve may be advantageously provided with a concentrically disposed mass or flywheel. With this arrangement the rotating assembly comprising the bobbin, the textile strand wound thereon and the bobbin carrying sleeve with its flywheel rotates about its center of mass which may deviate from the axis of the driving base bearing, the spindle blade flexing while rotating to permit such deviation. When the center of mass of the bobbin and sleeve assembly changes due to changes in the irregularity of winding of the textile strand, the spindle blade flexes to a new position to permit rotation of the assembly about an axis through its new center of mass. With the described arrangement, vibrations are eliminated or reduced to the point where speeds appreciably higher than those previously considered safe can be employed.

Where a highly flexible spindle blade is employed and in operations where the eccentrically disposed mass is considerable, the spindle blade may bend while the spindle assembly is at rest

2

and when it is rotating at slow speeds to an extent that undesirable eccentric flopping of the bobbin occurs. Under such conditions, the self-centering of the bobbin at higher speeds may be delayed or prevented and harmful speed limiting vibrations result. In accordance with one aspect of the invention, any such undesirable flopping of the bobbin during acceleration is prevented by providing centrifugally governed centering means adjacent the lower end of the bobbin-carrying sleeve, which mechanism holds the bobbin and its carrying sleeve in a position physically concentric with the driving base axis when the spindle is at rest or is rotating at relatively low speeds, the centering means being retracted at a predetermined speed to permit free movement of the bobbin and its carrying sleeve to a position in which it rotates about its center of mass.

In describing the invention in detail, reference will be made to the accompanying drawings in which certain embodiments thereof are illustrated. In the drawings,

Fig. 1 is a vertical section of a spindle assembly embodying the invention with a bobbin shown mounted on the assembly;

Fig. 2 is a view on a reduced scale taken along line 2—2 of Fig. 1 and viewed in the direction of the arrows;

Fig. 3 is an enlarged sectional view of the upper portion of a modified form of flexible spindle blade and the upper end of the bobbin carrying sleeve connected thereto;

Fig. 4 is a sectional view on a more enlarged scale taken along the line 4—4 of Fig. 3 and viewed in the direction of the arrows;

Fig. 5 is a bottom plan view on an enlarged scale, showing centrifugally operated centering means employed in accordance with one aspect of my invention, the view being taken along the line 5—5 of Fig. 6; and

Fig. 6 is a sectional elevation of the mechanism illustrated in Fig. 5, taken along the line 6—6 of Fig. 5.

In the disclosed embodiment, my improved construction includes a driving base including a central rigid shaft 5 surrounded by a concentric driving pulley 6 integrally connected to the shaft by a top end flange 7. The rigid shaft 5 is journaled in a fixed tubular case 8 to rotate about a fixed axis by axially spaced bearings such as the spaced ball-bearings 9 and 10. The driving base may be rotated at the desired high speed by a belt B engaging the pulley 6.

A bobbin carrying sleeve 8 is connected to the driving base by an elongated flexible spindle

blade 12. The blade 12 may be fixed to the driving base in any suitable manner. As shown, the enlarged lower end portion 13 of the blade 12 is fixed by press fit in an axial opening extending within the shaft 5 and within a sleeve 14 which surrounds the blade end portion 13 for a short distance above the driving base flange 7.

The bobbin carrying sleeve S is hollow and is slightly tapered as shown to provide a tight wedge fit with the central bore of a bobbin 15 which is similarly tapered. In accordance with the invention, the spindle blade 12 extends throughout the length of the sleeve S within the central open bore thereof and is connected to the sleeve only at its upper end. This connection may be by means of a press fit between an enlarged head 16 on the spindle blade and a reduced head portion 17 on the sleeve as shown. At its lower end, the bobbin carrying sleeve S carries a circular flange 18 rigidly fixed to or formed integral with the sleeve and having an enlarged depending rim 19 of considerable mass, the flange and rim acting as a flywheel. The assembly thus far described is normally concentric with the axis of rotation of the driving base which is fixed by the spaced bearings 9 and 10, so that the center of mass of this assembly lies along that axis, and but for irregularities in the distribution of the textile strand on the bobbin 15 and possible imperfections in the bobbin itself, it will rotate truly and without vibration about such axis.

With the long flexible spindle blade 12 connected to the bobbin carrying sleeve S only at the upper end of the assembly, the rotative behavior of the assembly is much the same as that of a spinning top. When the center of mass of the assembly is altered because of irregularities in the winding of the textile strand 20 on the bobbin 15, or for any other reason, the assembly comprising the bobbin, the mass of strand carried thereby and the bobbin carrying sleeve S moves to a new position in which it rotates about its new center of mass which is then eccentric with respect to the fixed axis of the driving base determined by the bearings 9 and 10. Since after such movement the assembly rotates about its new center of mass, it does not vibrate. The spindle blade 12 bends while rotating to permit the deviation between the axis of rotation of the driving base and the new axis of rotation of the bobbin and sleeve assembly. The magnitude of this deviation changes with changes in distribution of the mass of textile strand on the bobbin, so that the structure automatically accommodates itself to the irregular mass distributions that take place in the normal course of the winding or spinning operation.

The flywheel formed by the flange 18 with its rim 19 materially reduces the magnitude of the deviation between the axis of rotation of the sleeve and bobbin assembly and the fixed driving base axis. The combined mass of the sleeve S and its flywheel is great as compared to that of the eccentrically disposed portion of the textile strand, and for this reason the deviation of the axis is small and is readily accommodated by the small clearance between the inner bore of the sleeve S and the spindle blade carrying base sleeve 14. This clearance limits the possible deviation so that if the assembly is started up with an eccentrically disposed load on the bobbin, the initial wide deviation that may occur during acceleration and before the assembly has reached a speed of rotation at which it centers itself about

an axis through its center of mass is limited by engagement of the sleeve S with the blade carrying base sleeve 14.

The spindle blade 12 should be quite flexible, and when formed of solid steel its dimensional proportions may be of the order of three thirty-seconds to three-sixteenths of an inch in diameter to a seven-inch overall length. With such a seven-inch spindle blade, a radial clearance of the order of two or three thirty-seconds of an inch between the inner wall of the bobbin sleeve near its base and the surface of the blade receiving base sleeve 14 is ordinarily satisfactory. The dimensional proportions here indicated are not critical and are given only by way of example.

According to a modification of the invention illustrated in Figs. 3 and 4, the spindle blade may be formed of a flexible resilient cable 21 of known construction made up of a plurality of superimposed layers of spirally wound fine gauge resilient wire 22, the successive layers of which are wound in opposite directions. This blade 21 may be secured to the head 17 of the bobbin carrying sleeve S by a press fit or in any other suitable known manner. The cable type spindle blade 21 is somewhat more flexible for its size than the solid steel blade 12 of the modification previously described, and hence may be preferred where there is a considerable deviation of the axis of rotation of the bobbin assembly from the fixed axis of rotation of the driving base.

In one form of the invention, an embodiment of which is illustrated in Figs. 5 and 6, centrifugally operated means are provided for holding the bobbin carrying sleeve and the bobbin in a position substantially physically concentric with the axis of the driving base while the assembly is stationary and while it is rotating at speeds below those resulting in the above-explained self-centering action. This is accomplished by providing a plurality of centrifugally movable centering arms 23 pivotally secured at symmetrically eccentric points to the lower face of the flywheel flange 18 at the lower end of the bobbin carrying sleeve S. The several arms 23, of which three are shown in the disclosed embodiment, are pivotally secured to the flange 18 by stud screws 24 and are formed at their outer ends to engage the outer surface of the spindle blade carrying base sleeve 14 at equally spaced points when in their inner or extended positions, as shown in full lines in Fig. 5. The several arms 23 are preferably interconnected by suitable mechanism to move in unison so that their sleeve-engaging ends 55 are concentric with respect to the physical axis of the sleeve S in all positions. In the disclosed embodiment, this is accomplished by a series of links 25 pivotally connected by stud screws 26 between equally eccentric points on the several arms 23.

The several arms 23 are spring loaded to move to and remain in their inner positions in engagement with the base sleeve 14 until the bobbin and sleeve assembly has accelerated to a rotative speed at which it will center itself about its center of mass. I prefer to employ spring means that provides a maximum loading when the arms 23 are extended to engage the sleeve 14, so that as soon as the critical speed is reached, the arms 23 will immediately move to their outermost or retracted positions in which their ends clear the opening at the lower end of the sleeve S, as shown in broken lines at 23' in Fig. 5. One arrangement suitable for this purpose is illustrated.

Three levers 27 are pivotally secured to the

flange 18 by stud screws 28, one lever 27 being disposed adjacent and outside of each arm 23. The inner end of each lever 27 carries a roller 29 that engages the outer face of the adjacent arm 23. The levers 27 extend inward substantially radially from their pivotal supports, the arrangement being such that with the arm 23 in its innermost position, the lever 27 is displaced by a small angle α from a radial position. A tensioned spring 30 is secured to each lever 27 and to a post 31 on the flange 18 biases the lever toward a radial position and so biases the arm 23 toward its extended innermost position. An adjustment screw 32 with a lock nut 33 thereon is provided to permit adjustment of the spring tension and a stop post 34 limits the outward movement of the lever 27 to a position at which the arm 23 just clears the central opening in the sleeve S.

With the arrangement described, when the critical speed is reached, the centrifugal force acting on the arms 23 overcomes the load imposed by the springs 30. This load is at its maximum when the arms 23 are in their innermost positions since outward movement of the levers 27 increases the lever arm through which the arms 23 act on the springs 30. As a result, the arms 23 immediately snap to their outermost or retracted positions at the critical speed, moving the levers 27 to retracted positions against their stop posts 34, as illustrated in broken lines at 27' in Fig. 5. The bobbin carrying sleeve S and bobbin 15 are then free to center themselves about their center of mass in the manner explained above.

I claim:

1. A spindle assembly for rapidly rotating a textile strand bobbin comprising a rigid driving base, a pair of axially spaced bearings supporting said base to rotate about a fixed substantially vertical axis, an elongated flexible blade formed of superimposed layers of oppositely spirally wound wire fixed to and extending vertically upward from said base and lying along the fixed axis of rotation of said base when the blade is in the unflexed condition, and a hollow elongated bobbin supporting sleeve surrounding and substantially coextensive with said blade and fixed adjacent its upper end to the upper end portion of said blade, said sleeve and said blade being radially spaced apart except at their point of connection.

2. A spindle assembly for rapidly rotating a textile strand bobbin comprising a rigid driving base, a pair of axially spaced bearings supporting said base to rotate about a fixed substantially vertical axis, an elongated flexible blade formed of superimposed layers of oppositely spirally wound wire fixed to and extending vertically upward from said base and lying along the fixed axis of rotation of said base when the blade is in the unflexed condition, a tubular bobbin supporting sleeve surrounding and substantially coextensive with said blade and fixed adjacent its upper end to the upper end portion of said blade but spaced from said blade elsewhere, and a flywheel fixed concentrically to said sleeve at its lower end.

3. A spindle assembly for rapidly rotating a textile strand bobbin comprising a rigid driving base, a pair of axially spaced bearings supporting said base to rotate about a fixed axis, an elongated flexible blade fixed to and extending from said driving base and lying along the fixed axis of rotation of said base when the blade is in the unflexed condition, a hollow elongated bobbin supporting sleeve surrounding and substantially coextensive with said blade and fixed adjacent its upper end to the upper end portion of said

blade, said sleeve and said blade being spaced apart except at their point of connection, a plurality of arms carried eccentrically by said bobbin supporting sleeve adjacent its lower end and movable inwardly and outwardly with respect to said blade, and spring means biasing said arms inwardly into centering contact with said driving base, said arms being movable outward by centrifugal force from such centering contact when the speed of rotation of the spindle assembly reaches a predetermined value.

4. A spindle assembly for rapidly rotating a textile strand bobbin comprising a rigid driving base, a pair of axially spaced bearings supporting said base to rotate about a fixed axis, an elongated flexible blade formed of superimposed layers of oppositely spirally wound wire fixed to and extending from said base and lying along the fixed axis of rotation of said base when the blade is in the unflexed condition, a hollow elongated bobbin supporting sleeve surrounding and substantially coextensive with said blade and fixed adjacent its upper end to the upper end portion of said blade, said sleeve and said blade being radially spaced apart except at their point of connection, a plurality of arms carried eccentrically by said sleeve adjacent its lower end and movable inwardly and outwardly with respect to said blade and spring means biasing said arms inwardly into centering contact with said driving base, said arms being movable outward by centrifugal force from such centering contact when the speed of rotation of the spindle assembly reaches a predetermined value.

5. A spindle assembly for rapidly rotating a textile strand bobbin comprising a rigid driving base, a pair of axially spaced bearings supporting said base to rotate about a fixed axis, an elongated flexible blade fixed to and extending from said driving base and lying along the fixed axis of rotation of said base when the blade is in the unflexed condition, a tubular bobbin supporting sleeve surrounding and substantially coextensive with said blade and fixed adjacent one end to the outer end portion of said blade, said sleeve and said blade being radially spaced apart except at their point of connection, a circular flange concentrically fixed to and extending horizontally from said sleeve at its other end, a plurality of arms pivotally connected to said flange and movable outward substantially radially of the assembly by centrifugal force, said arms engaging said driving base and centering said bobbin supporting sleeve about an axis of said driving base when in their innermost positions, means connecting said arms to move in unison and spring means connected to bias said arms to move to their innermost positions.

6. A spindle assembly for rapidly rotating a textile strand bobbin comprising a rigid driving base, a pair of axially spaced bearings supporting said base to rotate about a fixed axis, an elongated flexible blade fixed to and extending from said driving base and lying along the fixed axis of rotation of said base when the blade is in the unflexed condition, a tubular bobbin supporting sleeve surrounding and substantially coextensive with said blade and fixed adjacent one end to the outer end portion of said blade, said sleeve and said blade being radially spaced apart except at their point of connection, a circular flange concentrically fixed to and extending horizontally from said sleeve at its other end, a plurality of arms pivotally connected to said flange and movable outward substantially radially of the assem-

bly by centrifugal force, said arms engaging said driving base and centering said bobbin supporting sleeve about the axis of said driving base when in their innermost positions, means connecting said arms to move in unison, and spring means connected to bias said arms to move to their innermost positions, said spring means exerting their maximum force when said arms are in their innermost positions.

7. A spindle assembly for rapidly rotating a textile strand bobbin comprising a rigid driving base, a pair of axially spaced bearings supporting said base to rotate about a fixed axis, an elongated flexible blade fixed to and extending from said driving base and lying along the fixed axis of rotation of said base when the blade is in the unflexed condition, a tubular bobbin supporting sleeve surrounding and substantially coextensive with said blade and fixed adjacent one end to the outer end portion of said blade, said sleeve and said blade being radially spaced apart except at their point of connection, a circular flange concentrically fixed to and extending horizontally from said sleeve at its other end, a plurality of arms pivotally connected to said flange and movable outward substantially radially of the assem-

8
bly by centrifugal force, said arms engaging said driving base and centering said bobbin supporting sleeve about the axis of said driving base when in their innermost positions, means connecting said arms to move in unison, pivotally supported levers engaging said arms and springs biasing said levers to move said arms to their innermost positions, said levers extending radially inward of said flange from their pivotal supports to their points of engagement with said levers whereby the bias of said levers is reduced as said arms move outward.
